UNITED STATES PATENT OFFICE

1,983,463

TAPE OF CHECKS

Harry T. Kingsbury, Keene, N. H., assignor to
 Kingsbury Mfg. Company, Keene, N. H., a corporation of New Hampshire

Original application August 29, 1931, Serial No.
 560,222. Divided and this application May 11,
 1933, Serial No. 670,544

5 Claims. (Cl. 281—5)

This invention relates to improvements in tapes of checks of the type comprising a series of initially joined checks which are severed along substantially transverse lines of the tape for individual employment of the checks.

The present application is a division of my co-pending application Serial No. 560,222, filed August 29, 1931, describing a mechanism employing such a tape of checks for the automatic delivery of the individual checks.

One of the features of the present invention is the provision of a tape of checks in which the strip forming the tape has weakened portions at intervals along its length corresponding to the junctions of two adjacent checks, at which the checks may be severed from one another.

Another feature of the present invention is the provision at such points of pluralities of apertures in longitudinally spaced relationship from one another whereby to facilitate the mechanical severing of the tapes from one another, for example in the manner described in my aforesaid application.

An illustrative form of tape according to this invention is shown on the accompanying drawing, in which:

Figure 1 is a view showing a portion of the tape and illustrating three complete checks and portions of two other checks.

Figure 2 shows two checks in their severed condition.

Figure 3 shows the manner of cooperation of a mechanism such as that described in my aforesaid co-pending application with the tape for producing a mechanical severing of the checks. This figure corresponds to Figure 7 of the aforesaid application.

In the drawing, Figure 1 shows three complete checks A, B and C, which may have any desired indicia on the faces thereof. Such checks are employed in many ways, in cafeterias, ticket offices, etc.

At the junction of the ends of two adjacent checks are provided in this illustrative form the lateral notches 69 and a central aperture 72 in alignment therewith. Between the aperture and notches are left the connecting webs 70 providing lateral margins to the aperture. Opposite the ends of these webs are the apertures 71 which are in transverse alignment with one another and are longitudinally spaced from the line of aperture 72 and notches 69, and extend for a transverse distance substantially corresponding to the width of the webs 70, and thus spaced longitudinally and also staggered or

spaced transversely with relation to the aperture 72 and notches 69. Thus transverse connecting portions join the individual checks at the points marked by dotted lines 75 in Figure 1, these portions being later severed along lines 60 which extend substantially longitudinally of the tape.

In the employment of such a tape, with the machine of my aforesaid application, for example, the tape is moved in the direction of the arrow in Figure 3. A tearing arm 51 is caused to move at a greater speed than the check B, while the check A is retarded in its movement so that a kink is formed at the junction of the two checks in the manner shown in Figure 3. 70 The tearing arm 51 enters the aperture 72 and presses upward on the rear end of check A so that this check then presents its slots 71 to the tearing fingers 35. As the check A continues in its forward movement the fingers 35a cause a 75 tearing of the tape and thus a severing of the checks. This tearing occurs along the dotted lines 75 of Figure 1, to produce the torn edges 75 in Figure 2.

It is obvious that the invention is not limited 80 solely to the particular form of execution shown, but that it may be modified within many ways of the scope of the appended claims.

Having thus described the invention, what I claim as new and desire to secure by Letters 85 Patent, is:

1. A tape of checks comprising a strip having notches and apertures therein in transverse alignment and separated by connecting webs, and further apertures in alignment transversely 90 of the strip and aligned lengthwise of the strip with said webs.

2. A tape of checks comprising a strip having lateral notches between the ends of adjacent checks, at least one web integrally joining each 95 two adjacent checks, and an aperture in the strip in longitudinal alignment with and extending for substantially the transverse distance of said web.

3. A tape of checks comprising a strip having lateral notches between the ends of adjacent checks, the strip also having integral junction webs located transversely between said notches, and apertures longitudinally offset from and aligned with said webs.

4. A tape of checks comprising a strip having at the junction of two adjacent checks at least one aperture and longitudinal webs providing lateral margins for said aperture, said strip also being transversely weakened at places in longi- 110

tudinal alinement with said webs and offset longitudinally from said aperture.

5. A tape of checks comprising a strip having at the junction of two adjacent checks a transversely extending connecting portion, said tape being weakened adjacent said connecting portion at staggered places on one and another

side of said connecting portion, the lateral margins of successive weakened places being substantially in longitudinal alinement so that the connecting portion is adapted to be torn through in a longitudinal direction between said places in severing the checks. 80

HARRY T. KINGSBURY.
